UNITED STATES PATENT OFFICE.

JOHN B. DAVIS, OF LANSDOWNE, PENNSYLVANIA, ASSIGNOR TO THE S. S. WHITE DENTAL MANUFACTURING COMPANY, OF PHILADELPHIA, PENNSYLVANIA, A CORPORATION OF PENNSYLVANIA.

COLLAPSIBLE TUBE.

1,122,868.

Specification of Letters Patent.

Patented Dec. 29, 1914.

Application filed December 11, 1912. Serial No. 736,056.

To all whom it may concern:

Be it known that I, JOHN B. DAVIS, a citizen of the United States, residing in Lansdowne, county of Delaware, State of Pennsylvania, have invented certain new and useful Improvements in Collapsible Tubes, of which the following is a specification.

My invention relates to improvements in collapsible tubes such as are employed for holding and dispensing liquids, viscous and plastic substances; for example, tooth paste, soap paste, etc.

The collapsible tube forming the subject of my invention is of a character well known in which the material is caused to be discharged from the discharge opening by means of a pressure of compression exerted thereupon at a point removed from the discharge opening. It has been found in the use of these tubes for holding and dispensing substances of the character mentioned, for example, tooth paste, that after the quantity of paste desired has been squeezed from a tube on to a tooth brush and the tube laid down, a quantity of the paste will escape from the discharge opening which not only results in waste of paste but causes the tube itself around its discharge end to present an unattractive appearance. Moreover, the drying of the paste in some cases interferes with the replacing of the screw cap in position to close the discharge opening.

My invention has for its object to provide means to prevent the escape of material, such, for example, as tooth paste, from the discharge opening of the tube after the pressure of compression thereupon has been removed. To accomplish this end, I have provided means interiorly of the tube which, while permitting the material to be discharged when subjected to pressure, acts to cause a cessation of the discharge of the material from the tube immediately upon the cessation of such pressure. One form of means employed by me for this purpose consists of a disk-like member of flexible and resilient material which extends transversely of the tube adjacent to the discharge end thereof and which upon the cessation of pressure upon the tube to cause the discharge of the material therefrom operates to effect the result hereinbefore stated.

In order that my invention may be more

readily and fully comprehended, reference 55 may be had to the accompanying drawing in which convenient forms of embodiment are shown. However, it should be understood that changes in the details of construction may be made within the scope of 60 the claims without departing from my invention.

In the drawings,—Figure 1 is a view showing a tube partly in elevation and partly in longitudinal section; Fig. 2 is a 65 view, at right angles to that of Fig. 1, showing a tube partly broken away and with the cap or closure removed and being also shown partly in longitudinal section and the disk being shown in position occupied 70 when the material is being expelled from the tube by a pressure of compression; Fig. 3 is a view in perspective of the disk shown in Figs. 1 and 2; Fig. 4 is a similar view of a disk of modified construction; and Fig. 5 75 is a similar view of a disk showing still another modified construction.

Referring to the drawings, 1 designates a tube one end of which is flattened, as indicated at 2, in a well known manner. The 80 tube consists of flexible material whereby the same is rendered collapsible under pressure so that such pressure causes the discharge of the material therefrom. As a result of such pressure the tube is collapsed or 85 flattened out. At one end of the tube its walls are non-collapsible and are extended inwardly, as shown at 3, and terminate in a neck 4, which is closed by means of an integral plate 5 which plate 90 is provided with an elongated discharge opening 6. Such opening may be of any other shape desired. The opening 6 is adapted to be closed by means of a closure consisting of a cap 7 having internally screw 95 threaded sides for engagement with the external screw threads of the neck 4. To insure a water tight closure of the opening 6 a washer 8 is provided in the bottom of the closing cap 7. As thus far described, the 100 construction is such that, as already stated, the material would continue to escape after the cessation of pressure upon the collapsible tube. For the purpose of preventing such continued escape of the material or 105 substance, such, for example, as tooth paste, indicated by the reference numeral 9, I have provided the disk 10 of resilient ma-

terial situated interiorly of the tube 1 within the material 9. The disk 10 is unsupported except by the material 9 within which the said disk may be described as floating. 5 The said disk 10 may consist of any material possessing the requisite quality of resilience and elasticity, but as a result of experiments thus far made, I prefer to use celluloid. For the purpose of enabling the 10 material to pass beyond the disk 10 toward and through the discharge opening 6, I have provided a curved slit 11 in the said disk thereby forming a tongue-like part 12, which in effect is a check valve, for closing 15 the space within the slit 11. The edges of the disk 10 are situated at the point of junction between the upright walls of the tube 1 and the inclined portion 3 thereof.

The edge of the disk is prevented from 20 forward movement by reason of its contact with the inclined part 3 of the tube so that when pressure is exerted upon the end of the tube opposite the discharge opening 6 therein the material 9 in the tube, being 25 more or less mobile, transmits such pressure to the said disk and causes a flexing of the same, as is indicated in Fig. 2, and also causes a flexing of the valve portion 12 to provide an opening for the passage outwardly of the material 9 as indicated by the 30 arrow 13. Upon the cessation or discontinuance of the pressure upon the tube and upon the material 9 therein, the resilient disk returns to and assumes its normal position, 35 indicated in Fig. 1. In doing so it tends to create a vacuum in the space between the said disk and the discharge opening 6 and thereby causes a retraction of the material 9 away from the said discharge opening so 40 that the escape of the same therethrough discontinues or ceases immediately upon the cessation of pressure.

Instead of providing the disk 10 with a slit of the curvature shown in Figs. 1 and 45 3, I may provide the same with a slit of different shape or form. In the modified construction illustrated in Fig. 4, I have shown a disk 10 provided with a straight slit 14 instead of a curved slit such as is shown in 50 Figs. 1, 2 and 3. If a disk having a straight slit 14, such as shown in Fig. 4, be placed in proper position in a tube, as indicated in Figs. 1 and 2, and pressure applied as before described, it will be bent or flexed and such 55 slit will open sufficiently to permit the material 9 in such tube to pass therethrough. Upon release of pressure from the tube and the contained material the said disk will return to normal position, the opening through 60 the said slit simultaneously closing. The return of the disk to normal position will effect a suction tending to create a vacuum in the tube between the said disk and the discharge opening 6 and thereby cause the 65 material to recede from toward the said

opening and thus prevent the further escape of the material from the said opening after the pressure upon the tube shall have been discontinued.

In Fig. 5 I have shown a disk 10 having 70 a plurality of curved slits 15 therein. These slits while curved have their opposing ends positioned farther away from each other than is the case with the slit 11, but the resilience of the material is such that there 75 is a bending of the tongues 16 formed by the said slits, in addition to the bending or flexing of the disk 10 as a whole, whereby the passage of the material 9 through the said slits 15 is facilitated. The operation of the 80 disk having a plurality of slits as is shown in Fig. 5 is substantially the same as that of the operation of the disks having the construction shown in Figs. 1 to 3 and Fig. 4 and need not be repeated.

In the several forms of construction the passage-ways through the disks are such as to offer more or less resistance to the passage of the material 9 therethrough and thereby insure the flexing of such disks as described; 90 also in the several forms the openings in the disks formed by the slits close simultaneously with the return of said disks to normal position.

I claim:

1. A collapsible tube of the character described having a discharge opening therein from which the substance in the tube is discharged when subjected to a pressure of compression, and the said tube being provided with a resilient disk having means for permitting the passage of the substance therethrough situated therein within the region adjacent to the said discharge opening and extending transversely of the tube and the said tube having a portion with which the edge of the said disk contacts to limit the movement of the said edge in one direction and the said disk flexing and unflexing as a result of pressure and release of pressure upon the said tube and the substance contained therein whereby the central body portion thereof moves toward and from the said discharge opening, the movement of the said disk away from the said discharge 115 opening upon the release of pressure operating to prevent a further discharge of substance from the tube upon the cessation of such pressure.

2. The combination of a collapsible tube 120 for containing substances of the character described, said tube having a discharge opening, and a disk situated in the said tube within the region thereof adjacent to the said discharge opening, the said disk being disconnected from the walls of said tube and having a vibratory movement toward and from the said discharge opening upon the application of pressure to and the release of the same from the said tube and the 125 130

substance contained therein, and the said disk having means for permitting the passage of the substance therethrough upon the application of such pressure.

5. The combination of a collapsible tube for containing and dispensing substances of the character described having a discharge opening therein, a disk situated in the said tube within the region adjacent to the said discharge opening and extending transversely of the said tube, the said tube having means for preventing movement of the edge of said disk toward the said discharge opening when a squeezing pressure is applied to the said tube and the substance therein, the said disk having at such time a flexing movement toward such opening and the said disk being provided with means to permit the passage of the substance in the tube beyond the said disk to the discharge opening when the said tube and the substance therein are squeezed, and the said disk having a flexing movement away from the said discharge opening for the purpose stated upon the release of such squeezing pressure.

4. The combination with a collapsible tube for holding a mobile substance, said tube having a discharge opening, of a resilient disk situated in said tube transversely thereof within the region adjacent to said discharge opening, the said tube having means for engagement with the edge of said disk to limit movement thereof in one direction and the said disk having means to permit the passage of such substance to the discharge opening upon the application of a pressure of compression to the tube, and the force of such pressure being transmitted through said substance to said disk causing a flexing of the same toward the said discharge opening and the return of said disk to unflexed position upon the cessation of such pressure operating to prevent a further discharge of substance from said tube.

5. A collapsible tube for holding a mobile substance having an opening for the discharge of said substance and being provided with a disk situated within and extending transversely of said tube in cooperative relation with respect to said opening and being unsupported except by said mobile substance, and the said disk having a normally closed opening therein.

6. A collapsible tube for holding a mobile substance having an opening for the discharge of said substance and being provided with an elastic disk situated within and extending transversely of said tube in cooperative relation with respect to said opening and being unsupported except by said mobile substance, and the said tube having means to limit movement of the said disk in one direction, the said tube permitting

free movement of the disk in the opposite direction, and the said disk having a normally closed opening therein.

7. A collapsible tube having a discharge opening and also having an elastic disk positioned interiorly thereof, the said tube having means coöperating with the edge only of said disk to maintain it in spaced relation with respect to the said discharge opening, and the said disk having a valve controlled opening therein.

8. A collapsible tube having a discharge opening and also having an elastic disk positioned interiorly and transversely of said tube and the said tube having a part which coöperates with the peripheral edge portion of said disk to maintain it in spaced relation with respect to said opening, said disk being cut to form an opening normally closed by a tongue.

9. A collapsible tube having a discharge opening and also having an elastic disk positioned interiorly and transversely of said tube, and the said tube having means coöperating with the peripheral edge portion of said disk to maintain it in spaced relation with respect to said opening, said disk being cut to form an opening normally closed by a tongue, said tongue comprising an integral part of the said disk.

10. A collapsible tube for holding a mobile substance having a discharge opening and also being provided with a floating disk situated interiorly thereof, the said disk being positioned in operative relation with respect to said discharge opening, and being provided with a valve controlled opening.

11. A collapsible tube having a discharge opening and also having a disk positioned interiorly and transversely of the said tube and the said tube having a part which coöperates with the edge portion of said disk to maintain it in spaced relation with respect to said opening, said disk being cut to form an opening therein.

12. The combination with a collapsible container having an orifice, of a resilient retractor located within the tube near the discharge end thereof.

13. In combination, a collapsible tube formed with an outlet opening, and a resilient retractor having an outlet and located in proximity to the opening in the tube whereby when pressure is applied to the tube to force material therefrom the resilient retractor will flex with the movement of said material and when pressure is removed the said retractor will assume its normal position and draw the excess material extended beyond the opening back into the tube.

14. In combination, a collapsible tube having a reduced end formed with an outlet opening, the tube being closed at its opposite end, a resilient plate disposed in the

4

tube and abutting against the reduced end portion, the resilient plate having an opening whereby when the pressure is applied to the closed part of the tube to eject the material the plate will flex and when pressure is released from the tube the plate will assume its normal position and retract the surplus material from beyond the opening back into the tube.

10 15. In combination, a tube for plastic material comprising a collapsible portion closed at one end and a non-collapsible contracted portion formed with an outlet opening, a resilient disk having an opening and 15 located in proximity to the contracted portion, whereby when pressure is applied to the collapsible portion to eject the plastic material the disk will flex and when pressure is removed the disk will assume its normal position and retract the surplus material from beyond the opening back into the tube.

16. In combination, a collapsible tube open at one end and closed at its opposite 25 end, and means including a resilient plate located in the tube for retracting surplus material, said plate flexing when pressure is applied on the tube to collapse same to force material through the opening, and

said plate creating a vacuum when pressure is applied on the tube is removed and thereby drawing the surplus material from outside the tube into the opening.

17. A paste-containing tube having a resilient member supported in its discharge end to flex toward the outlet under the pressure of the paste in the act of expelling the same from the tube and to return by its own tension when the expelling force ceases, thereby causing a recession of the paste 40 from said outlet.

18. In combination with a compressible paste-containing tube having an outlet, a disk supported in the tube near the outlet and having a resilient portion flexible toward the outlet under the pressure of the paste while the latter is being expelled by the compression of the tube, said resilient portion returning under its own tension when the expelling force ceases to cause a 50 recession of the paste from the outlet.

In testimony that I claim the foregoing as my invention, I have hereto signed my name this 10th day of December, A. D. 1912.

JOHN B. DAVIS.

In the presence of—

Wm. J. RUSSELL,

HARRY R. BARBER.
